FISHING-TOOL.

1,202,232.

Specification of Letters Patent.

Patented Oct. 24, 1916.

Application filed January 20, 1910. Serial No. 539,171.

To all whom it may concern:

Be it known that I, EDWARD J. SHARP, a citizen of the United States, residing at Los Angeles, in the county of Los Angeles and State of California, have invented a new and useful Fishing-Tool, of which the following is a specification.

This invention relates to a tool adapted for use in recovering from pump tubing and the like, sucker rods and the like, which may become detached either by breakage or by the unscrewing of parts inside the tubing at a distance below the top thereof.

It frequently occurs that the sucker-rods of oil well pumps become separated or broken leaving sections of the rods at great distances below the surface of the ground and from some cause such rods may become bent and twisted inside the tubing thus adding greatly to the difficulty of withdrawing them from the tubing. In fishing out sucker-rods from pump tubing it is important that when the sucker rod has been once lifted it must not be dropped, because the pump mechanism at the bottom of the tubing is liable to be injured if the sucker rod falls onto it from any considerable height.

An object of this invention is to provide a tool which is capable of being detachably connected with a sucker rod or other appliance of the same nature and which can be lowered into the tubing, and which will receive and automatically engage the upper end of the sucker-rod or other rod beneath the tool inside the tubing and tightly hold the same, so that when the tool is withdrawn it will carry with it the sucker rod thus engaged and will not drop the same until the sucker rod is otherwise supported, as by the usual elevators.

Another object is to effect the foregoing by a construction that admits of the sucker-rod hanging plumb while it is being withdrawn so that, if the broken end of said sucker-rod extends a considerable distance above the slip, as it often does, said broken end will not be tilted aslant relative to the axis of the pump tubing through which the sucker-rod is being withdrawn and so tends to catch on the sides of the pump tubing, especially at the joints of said tubing, and cause delay and trouble in raising the broken sucker-rod. The construction relied upon to

avoid such delay and trouble is the provision of a tubular body terminating at the top in a segmental extension and a shank fixed to the top of the segmental extension, said shank being laterally deflected or bent aslant to bring its upper end substantially in alignment with the axis of the body.

The invention is capable of embodiment in various forms with the object of engaging rods of various structures at their upper terminals, for the reason that where the sucker rod is broken between its ends a cylindrical portion must be grasped, and in case it unscrews or breaks at the box, the enlarged box of the rod must be engaged.

An object of the invention is to provide a light, cheap, simply and easily made tool capable of fishing out the sucker rods which become detached by unscrewing or by breaking of the box or rod between the box and pin or at any other place.

The accompanying drawings illustrate the invention.

Figure 1 is a perspective view of the fishing tool detached. Fig. 2 is an enlarged broken perspective detail of the same. Fig. 3 is a fragmentary axial section of the tool shown in Figs. 1 and 2 engaging a sucker rod inside a pump tube. Fig. 4 is a cross-sectional plan of the tool on line x^4 , Fig. 3. Fig. 5 is a fragmental axial section of another form of the tool on line x^5 , Fig. 6. Fig. 6 is a sectional plan view of the tool on line x^6 , Fig. 5. Fig. 7 is a fragmental perspective detail of another form of fishing tool illustrating the invention, as applied in pump tubing of large diameter. Fig. 8 is a cross section on line x^8 , Fig. 7. Fig. 9 is a fragmental axial section on line x^9 , Fig. 10, showing a form of the fishing tool adapted to engage a smooth rod. Fig. 10 is a plan in cross section upon line x^{10} , Fig. 9. Fig. 11 is a view of one of the slips looking at the tip thereof. A section of the tubular body is also shown. Fig. 12 is a fragmental view of the lower end of said slip.

The fishing tool comprises a tubular body 1 having a shoulder 2 and terminating at the top in an upward extension 3 above the level of the shoulder, and a slip 4 running on the extension and adapted to contract the passage formed by the bore of the body adjacent the shoulder 2. Said slip may be va-

riously constructed and may be variously connected with the body of the tool to slide up and down therealong when the tool is in fishing position.

- 5 In the form shown the slip is slidably fastened to the body of the tool by means of a stud running in a slot 5 in the upward extension 3. Said stud in many instances is a bolt or rivet 6 fastened in the slip and extending through the slot and provided with a dove-tailed or flaring head 7, the walls of the slot being inwardly converging to loosely fit the head and to retain the same while allowing the head to be flush with the outer 15 grooved face of the extension.
- In the form shown in Figs. 1, 2, 3 and 4 the slip is an oblong body having a wedge-shaped tip 8, the end of which is grooved, as at 9, to conform to the surface of the box 10 of the sucker-rod 11 to be caught, so that as the tool is lowered in the tubing the slip 4 may be lifted by the box 10 until the same leans over above the shoulder 2. This form of slip is employed in a tool in which the lower portion is a cylinder as shown at 12 in Fig. 2 and the upper portion is a segmental extension 3 of said cylinder 12, said extension being tapered at the top as shown at 13 and there fastened by rivets 14 to a shank 15, the upper end of which is provided with a pin 16 for connection with the box, not shown, of the sucker-rod or other appliance by which the tool is to be operated. By reason of this construction the 35 tool can be made at very low cost by simply cutting a short piece of pipe at right angles to form the shoulder 2 extending part way across, and cutting away the pipe from said shoulder upward to form the segmental extension 3 and by then slotting said extension as at 5, riveting the slip 4 and the extension together by means of the rivet 7 and riveting the shank 15 in place on the segmental extension 3 by the rivets 14 said shank may be formed of a piece of sucker-rod provided on its upper end with the usual pin 16. In providing an extension above the shoulder formed by the tubular body said extension being segmental and the shank 50 being a rod fastened to the tip of the segment allows free passage for the upper end of the sucker rod, which may have been broken below its pin, so that the tool body though quite short may be run down along the broken sucker rod for a considerable distance thus allowing the slip to take hold of the broken sucker rod far below its top so as to give greater security against any liability that the rod may slip entirely through 55 the tool after the broken sucker rod has been gripped. Said shank 15 extends aslant from the top of the extension 3 to bring the pin 16 into alinement with the cylinder 12. The slip 4, slot 5 and stud 6 are relatively proportioned and arranged so as to allow the

inner straight face 17 of the slip to slide in between the body of the tool and the box 10 or the pin 18 after the shoulder of the pin 18 has come above the shoulder 2 of the tool body.

The shank 15 is elongated, being of considerably greater length, say $1\frac{1}{2}$ times as long as the cylinder and its segmental extension; and extends aslant over the extension and terminates at its upper end as shown at 16 in Fig. 2 in axial line with the cylinder 12, so that when the tool is lowered and the cylinder encircles the sucker-rod to be fished for the tool may pass down until the upper end as at 16 has passed the end of such sucker-rod without any stoppage of the tool, so that on the reverse movement a certain and secure hold upon the sucker-rod can be had by the tool. In practice, however, it is not desirable that the upper end of the sucker-rod should extend too far up and when the slip is engaged and the sucker-rod of the tool is drawn up, the sucker-rod hangs plumb and practically centrally of the tool, thus avoiding kinking or buckling of the rod or any liability of the end of the rod sticking out or catching upon joints of the tubing.

In practical use with the form shown in Figs. 1, 2, 3, 4, 11 and 12, the tool having been attached to the sucker-rod at the top of the well will be lowered into the pump-tubing 20 until the flaring shoe 21 of the tool comes to the rod. The external diameter of said flaring shoe corresponds approximately to the internal diameter of the pump tubing 20 in which it is to be used so that the sharp lower edge of the flaring shoe will enter between the body of the tool and the box or pin as the case may be of the rod to be fished, and this will cause the upper end of the rod to come into alinement with the tubing. The box or pin as the case may be will strike the lower end of the slip and will push the slip up until the shoulder of the pin passes the shoulder 2 of the tool and thereupon the slip will slide down inside the box or pin and the pin will lean over to bring the shoulder thereof immediately above the shoulder of the tool as shown in Fig. 3. When this has occurred and the straight face of the slip is behind the pin or box of the rod to be fished, said rod is positively engaged by the tool and cannot be released until the tool is sufficiently withdrawn from the pump tubing to allow the sucker-rod to be grappled and upheld by elevators or other device, not shown, whereupon the fishing tool may be lowered and the slip lifted up out of the way so that the fishing tool may be withdrawn from the sucker-rod.

In the form shown in Fig. 5 the slip 22 is provided with a barb 23 and with a toothed shank 24 to facilitate engagement with the rod, and the stud 25 is formed integral with

the shank of the barb and may be upset or otherwise loosely secured in the slot 5, so as to allow it to slide up and down.

In the form shown in Fig. 7 the slip 26

5 is provided with two arms 27 that are pivoted to the slip and are adapted to fall upon and rest on the shoulder 2 when the slip is down, and to thus support the shoulder of the pin.

10 In Fig. 9 the body of the tool is provided internally with an upwardly flaring serrated face 28 and the slip 29 is provided with a like face 30. Said faces 28 and 30 are adapted to be brought close together by the weight 15 of the slip to engage the cylindrical portion or shank of a sucker-rod which has been broken between its pin and box.

In all of the slips the tip is preferably tapered and grooved as shown at 9 in Figs. 20 11 and 12 so that when the tip reaches the broken box 10 on the top of the broken sucker-rod, it will not lodge inside said box instead of outside and therefore if the sucker-rod does not lean aside to pass the 25 slip at the first engagement therewith it will not catch on the tip in such a way as to prevent the tip from wedging it over into the leaning position when the slip is finally stopped at the upward limit of its movement above the shoulder.

The form shown in Figs. 1, 2 and 3 is desirable for smaller sized pump tubing in which there is but little space between the boxing 10 of the broken sucker-rod and the 35 wall of the tube. The form shown in Figs. 7 and 8 is designed for pump tubing that is considerably larger in diameter than the boxing 10 of the broken sucker-rod. In such cases there is so much space inside the 40 tubular body 12' that the sloping shoulder of the pin 18 of the sucker-rod seen in Fig. 3 might escape from the shoulder 2. Therefore pivoted arms 27 are provided to rest on the shoulder 2 and said shoulder 2 is 45 preferably recessed as shown at 31 to receive the arms 27 when they drop after the shoulder of the pin has passed the same, and to hold the arms from spreading apart so that when the tool is drawn up, the arms 50 27 which are spaced apart a distance only slightly greater than the diameter of the rod body 11, will be held from spreading apart when the sloping shoulder of the pin strikes them. The arms are rounded at their 55 ends to allow them to tilt up easily to pass the sucker-rod box and the pivots are set outwardly from the line of direction of the

arms when thus raised, so that the arms will fall by gravity to rest on the shoulder 2 when the sucker-rod box is passed.

It is understood that any of the slips may be serrated if desired, as shown in Figs. 5 and 9, it not being deemed necessary that the straight face 17 be smooth and plain as shown in Fig. 3; the form of slip shown 65 in Figs. 5 and 9 being capable of having arms 27 mounted thereon in the same manner as shown in Fig. 7.

By constructing the tool with a segmental extension 3 extending above the level of the 70 shoulder 2 a firm attachment for the shank 15 is provided and the requisite strength for the tool is secured at the sides of the slot 5 with ample space between the shank and the walls of the tubing 20 to accommodate 75 the end of the sucker rod which may be broken off above the joint, thus to allow the tool to be lowered down to the joint of the broken sucker rod in the same position shown in Fig. 3, whether or no, the 80 sucker rod has been broken at the joint, as shown, or at a considerable distance above such joint.

I claim:—

1. A fishing tool comprising a body having 85 a shoulder and an upward extension above the shoulder, a slip running on the extension and adapted to contract the bore of the body adjacent the shoulder and provided with pivoted arms spaced apart to receive 90 the body of a sucker-rod between them and adapted to rest on the shoulder when the slip is at its lower position.

2. A fishing tool comprising a body having 95 a shoulder, a slip adapted to run on the body above the shoulder there being a passage behind the shoulder and said slip being adapted to contract said passage and provided with a grooved and tapered tip, and also provided with shoulders, arms pivoted 100 to the slip above the shoulders and spaced apart and adapted to rest upon the shoulder and said body when the slip is in its lower position, thus to support the shoulder of a sucker-rod when the tool has been slipped 105 down over the same.

In testimony whereof, I have hereunto set my hand at Los Angeles, California, this 12th day of January, 1910.

EDWARD J. SHARP.
